GEORGE F. McDougall, of Portland, Oregon, assignor of one-half to John P. Winter, of Portland, Oregon

UNRAVELING MACHINE

Application filed July 27, 1929. Serial No. 381,588.

This invention pertains principally to the art of reworking woolen cloth that has been previously woven and disintegrating it into fibers and threads nearly approximating the 5 original length of fiber in the wool and permitting it to be carded and rewoven with a minimum quantity of new wool added. It is also useful for disintegrating any kind of woven fabric where it is desired to preserve 10 the original length of the fiber such as in paper making and the like.

What is known as shoddy machines have been in use for many years and also some types of unraveling machines, though none of the 15 latter so far as this inventor is informed have been successful and the art can be said to be almost if not entirely new.

In unraveling cloth, particularly that which is tightly woven, it will of course 20 be necessary to pull the threads out one or a slightly greater number at a time across the width of the cloth to be unraveled and in order to do this successfully the cloth must be fed to the unraveling device at a uniform 25 speed which will be a function of the speed of the unraveling device and the feed for the cloth must be of such construction that while it will positively feed the cloth toward the unraveling device, it will just as 30 positively hold it in very close contact to the unraveling device in order that the cloth may not be jerked away in chunks and for a further object that a piece of cloth to be unraveled may be firmly held up to a very short 35 end, such short end being an inevitable waste. These objects and others that will be more fully pointed out and explained in the subjoined specification and claims, are the functions of the structures illustrated and described, which constitute my present invention.

The following is a general description of the drawings accompanying this specification, in which each figure of the drawing is 45 mentioned, and its relationship explained in a manner supplementary to the detailed description of the specification.

Fig. I is a longitudinal elevation partly in section of the whole machine and is intended 50 to convey an idea of its general working prin-

ciples. Fig. II is a spacing diagram for the teeth on the toothed cylinder shown in Fig. I and its purpose is to indicate that the teeth thereon in the cylinder are in rows circumferentially and axially. Many different plans for spacing these teeth are possible so that this inventor does not claim this particular plan of spacing as an essential feature. Fig. III illustrates the comb plate in plan and Fig. IV is a section taken on the line IV—IV of Fig. III; and Fig. V is a projection of Fig. III and shows an end view. Fig. VI is an elevation showing an assembly of the presser feet and their spaced relation to each other and serves to indicate that though the presser feet are plural in number the entire surface of the fabric passing under them will be covered. Fig. VII is a plan of the pressure foot portion, top view, that contacts with the fabric to be held to the conveyor member shown in Fig. VIII. The purpose of this view is to clearly illustrate the slots and half-slots, 29 and 30, and to show that the half-slots, 30, will be a full slot when two such elements are assembled in adjacent position. Fig. VIII is a broken away portion of the toothed conveyor member and the toothed end of the comb plate member showing their general relationship and when taken in connection with the side view in the general drawing immediately underneath the reference letter A, is clearly understandable.

It is possible for a considerable variation in construction to be had without departing from the principle of my invention. I therefore do not restrict myself to the precise construction illustrated which will be regarded as partly diagrammatic in nature and serves only to illustrate the principles which are particularly pointed out in the claims.

My unraveling machine consists essentially of four major elements, a toothed disintegrating cylinder, a supporting comb plate member, a toothed conveyor belt member and a loaded presser foot member, together with their minor parts to render them capable of functioning as hereinafter set forth in detail. A toothed revolving cylinder, 10, having spaced rows of teeth, 11, which are preferably pointed, is mounted upon a shaft, 12,

and supported in bearings, 13, and which is capable of being revolved at a high rate of speed in the direction shown by the arrow on the drawing in Fig. I.

Fig. II shows a spacing plan for the teeth, 11, but this spacing plan may be varied widely from that shown by varying the construction of the co-operating elements. In Fig. I there is shown a frame member, which is diagrammatic in nature, that supports the various co-operating elements of my machine. At 15 is shown a conveyor belt having teeth on the working surface thereof. For the purpose of clarity and to avoid crowding in the drawing the links are shown to have one tooth on the back thereof, but in actual construction there will be a plurality of teeth of generally diamond pointed shape and they will be relatively of less height than shown in the drawings.

These teeth are in spaced longitudinal rows which are constructed by building the chain of alternate toothed links and smooth backed links; the smooth backed links being somewhat lower than the toothed links and in the assembly of the machine the toothed links will have their teeth in the same vertical plane as the circumferential rows of teeth on the cylinder, 10.

30 The teeth on the conveyor belt, 15, are indicated on the drawing by the numeral 16. Diagrammatic representation of an operative connection between the toothed cylinder, 10, and the conveyor belt, 15, is shown by the belt, 17, the mule stand, 18, and the gear 19 and the pinion, 20. This operative connection merely serves to indicate that there must be a maintained definite relation between the speed of the toothed cylinder, 10, and the forward speed of the conveyor belt, 15, and that the speed of the perimeter of the toothed cylinder, 10, will be very considerably in excess of the speed of the conveyor belt, 15.

Conventional representation of a fabric to be processed is shown at 21 where it is carried forward onto the conveyor belt, 15, by any convenient means and it is held to the conveying surface of the belt, 15, by the angled presser foot, 22, which is kept in close contact with the fabric and holds it firmly to the conveyor belt by means of the pivot, 23, bell crank lever, 24, fulcrum, 25, and the leading device, 26, which is shown here to be a compression spring.

55 Means for preventing the angled presser foot, 22, from riding too hard on the toothed portion of the conveyor belt, 15, is diagrammatically shown by the adjustable bolt, 26^a, which will be threaded into the stand, 27, and having a locknut, 28.

Fig. VII is a plan view of the presser foot, 22, and shows that the ends next to the revolving cylinder, 10, are slotted by the slots and half-slots, 29 and 30, in such a way that the teeth of the said revolving cylinder, 10, may

pass through the said slots represented by 29 and 30 and out of contact with the teeth, 16, and the presser foot, 22.

To provide for unevenness in the thickness of the fabric, 21, the presser foot, 22, is made up of an assembly of separate units, as shown in the elevation in Fig. VI, each with its own loading device so that it may act independently of all of the others and to prevent a lump or similar defect in the fabric from raising the entire holding device and allowing the fabric to be jerked forward by the revolving cylinder, 10.

I have heretofore pointed out the importance of firmly holding a fabric to be unraveled so that it may be positively fed forward to an unraveling device which in my present invention consists of the revolving toothed cylinder, 10, and the comb plate, 31, which is shown in operative relation to the other parts in Fig. I in plan in Fig. III; and a cross section of Fig. III on the line IV—IV is shown at Fig. IV.

This comb plate, 31, performs the absolutely essential function of picking up the fabric to be unraveled as it leaves the point of contact between the toothed conveyor, 15, and the presser foot, 22, which is indicated on the drawing by the letter A. The comb plate, 31, is adjustably supported on the frame, 14, by the bolts, 32, and is provided with an end-wise adjustment by the stud, 33, the lock-nuts, 34 and 35, and the lug, 36.

In Fig. IV is illustrated a preferred construction of the said comb plate, 31. It has grooves, 37, which terminate in a slightly curved point, 38, and an undercut, 39, and its relation to the toothed conveyor, 15, is clearly shown in Fig. VIII. In Fig. VIII it will be noticed that the longitudinal rows of teeth on the toothed conveyor, 15, are equal in number to the grooves, 37, the points, 38, and the undercuts, 39, and that the teeth on the conveyor belt are in the same vertical plane as the grooves, 37; that the teeth on the conveyor belt, 15, pass between the points, 38, down through the undercuts, 39, which are provided for their accommodation and thence to the reversely running portion of the conveyor belt, 15.

The points, 38, project between and below the working surface of the teeth, 16, and serve to pick up the fabric from the toothed conveyor, 15, and insure that it will not be driven down between the conveyor belt, 15, and the comb plate, 31. As the fabric to be unraveled reaches the point designated by A it is struck a penetrating blow by one of the teeth, 11, which are in circumferential rows, equal in number to and in the same vertical plane as the grooves, 37. The fabric will therefore be supported by two adjacent points, 38, while it is being penetrated by the tooth, 11.

As the speed of the toothed cylinder, 10, is much greater than the forward feed of 17

the fabric, 21, continued motion of the tooth, 11, will pull a thread intercepted by said tooth out of the twist and weave of threads running in the other direction and separate it therefrom.

5 It is essential in proportioning the speeds of the several parts of this device that the designer keep in mind that one or more of the teeth, 11, should contact with the fabric, 21, each time that the forward speed of the fabric, 21, is equal to a longitudinal space represented by the spacing of the thread, 21^a. This will serve to carry this thread away from and out of the fabric from which it is unraveled as represented by the mass, B.

10 15 When this pulling out of threads, 21^a, has progressed for an inch or more, the whipping action of the teeth, 11, upon the warp threads, represented by numeral 21^b, causes them to untwist and fray and be carried away in the same mass as the threads 21^a.

20 25 It will thus be seen that the action of this unravelling machine is wholly different from what is commonly known as a machine for making shoddy, which pulls and breaks fibers from the body of the cloth and that this, my invention, will leave the original fibers of the material composing the fabric in more nearly their original length, thereby increasing its 30 value for carding and reworking.

25 In feeding fabric to this machine to be unraveled, a better product will be obtained if it is skillfully applied to the toothed conveyor, 15, so that the threads, 21^a, are as near 35 as may be parallel to the axis of the toothed cylinder, 10.

30 40 Diagrammatic means for adjusting the tension of the toothed conveyor, 15, is shown at C and diagrammatic means for adjusting its vertical relationship to the toothed cylinder, 10, is shown at D and sprockets, C' and D' are shown as means for producing appropriate movement of the toothed conveyor, 15.

45 Having thus fully described and illustrated my invention so that a competent designer could build and operate one, what I claim as new and desire to secure by Letters Patent, is:

50 55 60 65 1. In an unravelling device, a chain belt conveyor member having spaced longitudinal rows of teeth on the conveying surface thereof and a plurality of loaded, ankled presser foot members co-operating with said working surface and adapted to hold a piece of fabric tightly between said teeth and said presser foot members while it is being carried forward at a selected rate of speed with a comb plate member of the character described having teeth lying between the teeth on the conveyor member with the points below the working surface of the conveyor teeth.

70 75 80 85 2. In an unravelling device, a chain belt conveyor member having spaced longitudinal rows of teeth on the conveying surface thereof and a plurality of loaded ankled presser

foot members co-operating with said working surface and adapted to hold a piece of fabric tightly between said teeth and said presser foot members while it is being carried forward at a selected rate of speed in combination with a comb plate member adjustably disposed at the delivery end of the conveyor member to pick up and support delivered fabric.

70 75 80 85 3. In an unravelling device, a belt conveyor member and means for imparting to it a selected speed, teeth on the working surface of said belt conveyor member, slotted ankled presser foot members adapted to keep fabric in close contact with said teeth and a comb plate adapted to receive fabric from said conveyor member at approximately the point where it is released from contact between said conveyor member and said presser foot members.

90 95 100 105 4. In an unravelling device, a chain belt conveyor member and means for imparting to it a selected speed, teeth on the working surface of said belt conveyor member, slotted ankled presser foot members adapted to keep fabric in close contact with said conveyor member and a comb plate adapted to receive fabric from said conveyor member at approximately the point where it is released from contact between said conveyor member and said ankled foot members.

110 115 120 125 5. In an unravelling device, a slotted angled presser foot member having slotted ends adapted to allow passage therethrough of the teeth of a revolving cylinder, in combination with a comb plate member to unravel fabric, said presser foot member co-operating with a toothed conveyor member to firmly hold a fabric to be operated upon by said toothed cylinder while supported by said comb plate.

120 125 130 135 6. In an unravelling device, a slotted ankled presser foot member having a slotted end adapted to allow passage therethrough of the teeth of a revolving cylinder, in combination with a comb plate member to unravel fabric, said ankled presser foot member in combination with a toothed chain belt conveyor member to firmly hold a fabric to be operated upon by said toothed cylinder and said comb plate.

135 140 145 150 7. In an unravelling machine, a chain belt conveyor member having spaced longitudinal rows of teeth on the conveying surface thereof and a longitudinally grooved comb plate member adapted to receive fabric conveyed by said belt conveyor member; said comb plate member having spaced teeth adapted to fall between and under the points of the longitudinal rows of teeth on said conveying surface of said belt conveyor member and a toothed cylinder, the teeth of which are spaced so that the points run in the grooves of the comb plate member.

150 155 160 165 8. In an unravelling machine, a chain belt conveyor member having spaced longitudinal

- and rows of teeth on the conveying surface thereof and means for positively driving said conveyor member at selected speed and a plurality of slotted anked presser foot members adapted to hold fabric firmly on said conveying surface, and unit means for loading said slotted anked presser foot members.
9. In an unraveling machine, a chain belt conveyor member having spaced longitudinal rows of teeth on the conveying surface thereof and means for positively driving said conveyor member at selected speed and a plurality of slotted anked presser foot members adapted to hold fabric firmly on said conveying surface; and independent means for loading said presser foot members.
10. In an unraveling machine, a chain belt conveyor member having spaced longitudinal rows of teeth on the conveying surface thereof and means for positively driving said conveyor member at selected speed and a plurality of slotted anked presser foot members adapted to hold fabric firmly on said conveying surface; and independent means for loading said anked presser foot members and a rigid toothed comb plate member the teeth of which fall between and below the points of the teeth on the conveyor member to support carried fabric.
11. In an unraveling machine, the combination of a revolvable toothed cylinder having teeth in spaced rows and a rigid comb plate member having slots to co-operate with said teeth, such slots being disposed so that each working tooth has a co-operating slot.
12. In an unraveling machine, the combination of a revolvable toothed cylinder having teeth in spaced rows and a rigid comb plate member having slots to co-operate with said teeth, such slots being disposed so that each working tooth has a co-operating slot and conveyor feed means to feed fabric to be unraveled at a positive uniform rate of feed.
13. In an unraveling device, a toothed cylinder having teeth in spaced rows, and a comb plate member having grooves spaced to correspond with the spacing of the teeth on the cylinder, and a receiving end of said comb plate member composed of points adapted to fall between and below the working surface of the teeth of a conveyor member.
14. In an unraveling device, a comb plate member of the character described and having points and being adjustably disposed in relation to a conveyor member of the character described, and having longitudinal grooves to receive the points of the teeth of a revolving toothed cylinder so that the points of said teeth of said revolving toothed cylinder will pass below the general plane of surface of said comb plate.
15. In an unraveling device, an anked presser foot member having a slotted end adapted to allow passage therethrough of the teeth of a revolving cylinder, in combination with a toothed surface conveyor member and a toothed cylinder having teeth in rows spaced to correspond to the slotted ends of the presser foot member.
16. In an unraveling device, a multiple toothed cylinder having bearings and adapted to be revolved and having the teeth in spaced rows on the perimeter thereof in combination with a comb plate member having longitudinal grooves with the same spacing as the teeth on the cylinder, said comb-plate member being adjustably disposed in relation to said cylinder so that the points of the teeth of the cylinder in revolving will pass through the grooves of the comb plate for the purpose specified.
17. In an unraveling device, a revoluble multiple toothed cylinder having bearings and having spaced rows of pointed teeth in combination with a grooved comb plate member of the character described and illustrated, and a chain belt conveyor member having a toothed conveying surface with the teeth in longitudinal rows and in the same plane as the teeth on the cylinder.
18. In an unraveling machine, a comb plate member having a plurality of longitudinal grooves on the working surface thereof, having slots at the receiving end in the same plane as the grooves and points at the receiving end thereof in substantially the same plane as the working surface, the said points being undercut to conform to the outline of a conveyor.
19. In an unraveling machine, the combination of a toothed conveyor member having longitudinal rows of teeth alternating with lower smooth surfaces, a loaded slotted anked presser foot member bearing upon the toothed surface of said conveyor member and a grooved comb plate having the grooves terminating in slots with points between the slots and said points bearing between the rows of teeth on the conveyor member on the smooth surfaces.
20. In an unraveling machine, a disintegrating cylinder having spaced rows of pointed teeth in combination with a comb plate member of the character described having longitudinal grooves in the same vertical plane as the rows of teeth on the cylinder and adjustably disposed in relation to said cylinder so that the teeth of the cylinder will pass through the grooves when the cylinder is revolved.
- GEORGE F. McDougall.
